UNITED STATES PATENT OFFICE.

MORRIS LEVITAN, OF NEW YORK, N. Y.

DESIGN FOR AN ELECTRIC-LIGHTING-FIXTURE PLATE.

Application filed May 12, 1926. Serial No. 17,669. Term of patent 3½ years.

To all whom it may concern:

Be it known that I, MORRIS LEVITAN, a citizen of the United States, residing at No. 868 Faile Street, borough of Bronx, city and State of New York, have invented a new, original, and ornamental Design for Electric-Lighting-Fixture Plates, of which the following is a specification, reference being had to the accompanying drawing, forming a part thereof.

Figure I shows a top plan view of the

plate, only a portion thereof showing the complete ornamentation, it being understood that the balance of the plate within the marginal border line is similarly finished.

Figure II shows a diagrammatic view in side elevation of the article shown in Figure I, the ornamentation being omitted.

I claim:

The ornamental design for an electric-lighting-fixture plate, as shown.

MORRIS LEVITAN.
